POT CLEANER

Edward S. Bradford, Jr., Longmeadow, Mass., assignor to Springfield Wire & Tinsel Co., West Springfield, Mass., a corporation of Massachusetts

Application November 5, 1934, Serial No. 751,471

3 Claims. (Cl. 15—208)

This invention relates to a pot cleaner or scouring utensil of improved species of the kind made from a strand of helically coiled tinsel wire ribbon. It may be made of a coiled strand with or 5 without a core but it is highly desirable, if a core is used, to have the core as well as its coiled covering material of elastic character so the strand as a whole may stretch and recoil lengthwise.

I will disclose the invention for illustration as 10 made of a coreless strand in connection with the accompanying drawing, in which—

Fig. 1 shows a length of strand indicating a coiled strand material of flattened tinsel ribbon, and arrangement of two sizes of coils to 15 make my utensil;

Fig. 2 indicates in a conventional way a balled mass of the strand in finished cleaner form;

Fig. 3 indicates in a conventional outline a mass in "door knob" shape for finished cleaner form;

Fig. 4 indicates in a conventional outline a mass in disk shape for finished cleaner form;

Fig. 5 is a conventionalized cross-section of the mass of Fig. 2 taken on any plane through the center of the ball form and intended to show the 25 nature of the ball mass as contrasted between its outer layers and inner core;

Fig. 6 is a section of coiled flattened filament wire drawn to scale, such as I use in the commercial forms of my invention for the small coil covering material; and

Fig. 7 indicates a winding spindle or stick such as I may conveniently use to wind my strand material to make various finished cleaners.

One way to make my improved article is to 35 start with a flat tinsel wire such as is now in common use for pot cleaners. The flat wire is first straight; it is then coiled for a long portion of its length, indicated by A—B in Fig. 1, with what I call large coils (larger than the coils commonly 40 used in pot cleaners), and is also curled for a long portion of its length, indicated by B—C, with what I call small coils that are of a size commonly used in pot cleaners. A commercial size for the small coils is shown in Fig. 6. A suitable proportion 45 between the small coils and large coils is shown in Fig. 1. The scale of the coils in Fig. 1 has been purposely enlarged for convenience. Also the coils are all shown somewhat conventionalized. Since they are made of very thin tinsel ribbon they sag and the spacing of the coils is usually less than that indicated.

With the strand thus prepared I wind it up into a mass so that the large coils 1 are all located in the central part and then well covered by winding 55 layers of the strand having the small coils 2.

The result is a relatively soft, puffy, centrally located mass L of large coils 1 covered by a relatively hard covering mass S of small coils 2 on the outside of the soft, puffy mass. This is indicated in Fig. 5, where the portion L is the section through the large coils and section S is that through the small coils of the combination of masses of coils making up the cleaner.

The article disclosed can be made up in many different ways. I prefer to make it of a single 10 strand as a convenience, and Fig. 1 is intended to show a single strand long enough for my purpose. But two or more parallel strands can be worked up together or the strand or large coils can be a 15 separate one (ends not joined) from the strand 15 of small coils. For an illustrative disclosure I have drawn the size of the coils in Fig. 1 to a suitable proportion in the relative size of coils for actual commercial use, but it can be varied of course and still embody the principles of large and small 20 coils for my purpose.

A convenient way to get the mass of either Fig. 2, or Fig. 3, or Fig. 4, is in the fashion of a ball wind, by which I mean one in which the turns or loops of each complete wind change their angle often enough to make a cross-grained series 25 of layers throughout the mass. Any winding operation that gives this cross-grained effect in the wind in all planes of the mass, is what I mean 30 by ball wind fashion in the operation of assembling the mass. This can be done by hand and it results in a mass that will not string out or readily unravel, because the turns are crossed in the mass and the coils interlock to prevent the strands 35 from separating over any substantial length. In 40 fact, the coiled springy tinsel wire tangles between coils enough to make a form that will spring back to shape after a lot of use.

A convenient hand tool for winding any of the 40 forms of Figs. 2, 3, and 4 is shown in Fig. 7. It consists of a spindle stick 3 having near each end a series of flexible wires 4 which bend very easily. The strand indicated in Fig. 1 of suitable length can be wound in successive "figure 8" loops on 45 stick 3 as a temporary core. The large coil portion is first wound on. The stick is slowly turned and the outer ends of the loops are passed over and between the wires 4 to hold them in spaced overlapping relation. This wind is the same as 50 that used by a boy in winding up a fish line or a kite string on a stick, except that wires 4 hold the loops apart and near the outer ends of the stick. The large coils 1 are first wound on and then their 55 mass is covered by winding on the strand portion of small coils 2. The winding slight tension is

enough to separate the otherwise more closely spaced coils along the strand. When the mass is built up on the stick it does not have its finished form. But by removing it from the stick (wires 5 4 bending to permit removal) the mass of coils has a distinct movement to the ball form of Fig. 2. By hand the mass of coils can be readily worked to any of the forms *b*, *d*, *f* of Figs. 2, 3, and 4. It will help, however, in getting the flattened mass 10 of Fig. 4 to make a longer wind on stick 3 than for the form of Fig. 2. The cross-grained "ball fast- 15 ion" winding and interlocked relation of the coils will appear in all forms shown and in other forms. For example, a ring-shaped form can also be made, using a suitable core or a hollow ball form and the relative arrangement of coils will be present.

The advantage of the article is in the functional character of the two kinds of coils combined in the mass of a single cleaner, and the way 20 they interlock and cooperate to tie the mass together. Those on the inside give an exceedingly puffy and springy nature to the cleaner. They push out the outer covering somewhat like 25 an air center will in a soft hollow rubber ball, or like eider down will in a feather pillow, while the outer covering does the scratching. So the outer covering is pushed out to give the desired handful of coils. The article will not pack up centrally or 30 get hard at the center to anywhere near the same amount under the same use as where the whole mass is a bunch of tangled small curls. The latter are desirable on the outside for scratching purposes, but not so desirable on the inside where 35 they never actually contact the pot to be cleaned. Furthermore, the larger open-work coils on the inside of the mass make the article easier to clean, as the grease will not get trapped so readily, since there is a larger space for it between 40 tangled coils and it can be washed out more readily. Other advantages will appear on analysis. Not the least of them is that a better cleaner can be made of the same size with less weight of material per unit than where the mass is made up 45 altogether, with the small coils wanted on the outside of the mass for scratching purposes as is the usual custom. These pot cleaners are made up in the millions and a saving of material with improved functions in each unit is of real importance. Nevertheless, the main advantage is 50 in the function of the article as a better scratcher.

for pots and pans and analogous cleaning purposes, particularly where a handful of scratching metal filament is desired. The article is ordinarily made up to supply one handful of coils. It is all metal and preferably has no points of attachment to anything else—as a handle or tying string or wire. As I have disclosed the preferred form, there are no hard spots in the article, and yet it will all hang closely together in a remarkable fashion. The central mass is softer than the 10 nature of the scratching coils ordinarily requires, and puffs out the whole cleaner for a highly desirable kind of cleaner.

What I claim is:

1. A pot cleaner comprising a central mass of 15 tangled coils of spring metal wire and a covering mass of definitely wound loops of said wire in flattened ribbon form of closely spaced helical coils, the covering mass constituting a substantial thickness of looped plies or layers of such wire, 20 the cleaner mass being characterized by the feature of substantially larger coils of wire in the central tangled mass than the helical coils of said covering mass whereby the cleaner has a softer puffer central mass made of spring metal coils as 25 compared to the covering mass of smaller coils.

2. A pot cleaner comprising a ball wound mass of a spring wire ribbon the strand of which is coiled in helical fashion along its length into a great number of coils per unit loop of the wound 30 mass, the coils in the central portion of the cleaner being larger than the coils in the layers forming the covering portion, the latter portion having a substantial depth and provided with relatively small coils to do the cleaning work 35 while the central portion is of substantial volume and provided with relatively large coils all interlocked and tangled together whereby a softer puffer central portion is in the cleaner than if the whole mass were made of said small coils.

3. A pot cleaner made of metal comprising a mass of wire coils the outer layers of which are made of flattened tinsel wire in closely spaced coils along its length, such layers being made up of wound loops of such coiled length, said loops 45 crossing and recrossing like a screen to tie the coils together in the mass while the central part of the mass is made of tinsel wire having larger coils interlocked and tangled together than the outer layers.
